UNITED STATES PATENT OFFICE.

WALTER VAN GUILDER, OF CHICAGO, ILLINOIS, ASSIGNOR TO STEWART-WARNER SPEEDOMETER CORPORATION, OF CHICAGO, ILLINOIS, A CORPORATION OF VIRGINIA.

TWO-WAY SWITCH.

Application filed September 29, 1922. Serial No. 591,205.

To all whom it may concern:

Be it known that I, WALTER VAN GUILDER, a citizen of the United States, residing in the city of Chicago, in the county of Cook and State of Illinois, have invented certain new and useful Improvements in Two-Way Switches, of which the following is a specification, reference being had to the accompanying drawings, forming a part thereof.

10 The purpose of this invention is to provide a two-way switch of simple and economical construction, particularly adapted for alternately energizing two circuits containing distinctive signals. It consists in 15 the elements and features of construction shown and described, as indicated in the claims.

In the drawings:—

Figure 1 is a front elevation of the switch 20 device with its several parts mounted together without the support or dash board upon which it is mounted in service.

Figure 2 is a section at the line, 2—2, on Figure 1.

25 Figure 3 is a section at the line, 3—3, on Figure 2.

Figure 4 is a detail section on an enlarged scale, at the line, 4—4, on Figure 3.

Figure 5 is a section of the line, 5—5, on 30 Figure 2, the casing and contents being broken away at both sides to disclose the operating handle in relation to the shaft at 5—5.

Figure 6 is a detail section at the line, 35 6—6, on Figure 5.

Figure 7 is a detail section at the line, 7—7, on Figure 2.

Figure 8 is a detail section at the line, 40 8—8, on Figure 2.

Figure 9 is a developed section in the arc line, 9—9, on Figure 3.

Figure 10 is a wiring diagram of the switch and the signal which it controls.

The structure shown in the drawings 45 comprises a casing in which are enclosed a contact carried by the switch lever and others mounted on the casing, said casing being designed and adapted to be supported upon the back side of an instrument board or other 50 mounting member of a motor vehicle to be served by the device, the face plate being mounted upon the opposite side of the board, the switch lever having a rock shaft provided with an operating handle, said shaft 55 extending through the board and through

the face plate, and having the operating handle at the forward side of the board, the construction being such that only the contacts mentioned enter into the circuit at any time, the switch lever, its rock shaft 60 and operating handle, and all parts of the casing and the face plate being excluded from the circuit. A special feature of the construction, as designed, is its adaptation for mounting upon a support or board of 65 any thickness, clamping the casing and the face plate together upon opposite sides of the mount or support, whatever it may be, the variation in thickness of said support being accommodated by the switch lever rock 70 shaft and its adaptation for telescoping through its bearings in the casing and through the switch lever held in the casing.

In the drawings the board or other support is indicated at A. The casing comprises two members, B¹ and B², which are sheet metal stampings in the form of flanged cups which are secured together with their cup cavities, 3 and 4, facing each other to form together a single chamber, said members being united by means of their similar flanges, 5 and 6, which have each diametrically situated notches, 7 and 8, and on a diameter at right angles thereto, lugs, 9 and 10, struck and folded from similar notches 9^a and 10^a, and said flanges having also diametrically opposite lugs, 11 and 12, and bolt apertures, 11^a and 12^a, therethrough, said lugs and apertures being in a diametric line bisecting the angle between the diametric lines in which the notches, 7 and 8, and the lugs, 9 and 10, respectively, are located. It results from this formation that the two members, B¹ and B², are identical in form, whereby when they are mounted upon each other with their cup cavities facing and combined, the lugs, 9 and 10, engage the notches, 7 and 8, while the bolt apertures, 11^a and 12^a, of each member are registered 95 with those of the other member. Said lugs, 9^a and 10^a, are clinched down over the flanges of the opposite case member respectively, and the registered bolt apertures serve for the bolts which clamp said casing and face plate hereinafter described, upon opposite 100 sides of the support, A. The casing members, B¹ and B², have apertures, b¹ and b², which are aligned when the said members are assembled, for mounting the bearings, 15 and 16 for the switch lever, 17, and its 105

shaft, 18. Said bearings, 15 and 16, are dimensioned longitudinally with respect to the depth of the cup cavities in the casing members, 3 and 4, to space apart their proximate ends when the parts are assembled, the amount of the thickness of the switch lever, 17, which is a flat spring bar. For engaging the switch lever with its rock shaft, 18, so as to be rotated by the latter, and to permit the latter to telescope through the bearings and through said lever for the purpose above indicated, a square opening is formed in said lever by striking and folding out of said aperture two lugs, 18^a, 18^a, which are folded to stand at right angles to the plane of the flat spring bar lever, and thereby constitute bearing surfaces at two opposite sides for the shaft, 18, which is square and fitted to said square aperture. The bearings, 15 and 16, at their opposite ends are interiorly diametered to the diagonal dimension of the square shaft, and at their proximate ends are counterbored to that diagonal dimension increased by the thickness along the diagonal line, of the lugs, 18^a, 18^a; so that the shaft has its four corners, and the lugs at their outer corners bearing in said journal bearings, 15 and 16. In order that these mere corner bearings may be adequate for centralizing the shaft and properly positioning the contact button hereinafter mentioned carried by the switch lever, the journal bearings, 15 and 16, are desirably of bronze, between which and the steel of which the shaft, 18, and the lever, 17, are composed there is a minimum wear. The switch lever carries at its free end a contact button, 20, insulated at its mounting on said switch lever. In the casing member, B¹, in the arcuate path of movement of the contact button, 20, there are mounted three contacts, 21, 22 and 23, each insulated at its mounting in the casing, and each provided with a stem extending out through the casing wall, adapted exteriorly for a circuit wire connection. The several contacts, 21, 22 and 23, are relatively shaped so that the contact, 20, is adapted to snap into engagement with the contact, 22, and when so engaged to be out of contact with both the contacts, 21 and 23, and so that when said contact, 22, is snapped out of contact with the contact, 23, on the side toward the contact, 21, it is in contact at its opposite sides with both said contacts, 21 and 22, and when snapped out of contact on the other side of the contact, 22, it is in contact at its opposite sides with both said contacts, 22 and 23. As illustrated, this relation or form of the several contacts is obtained by making all the contacts, 21, 22 and 23, like each axially hollow and interiorly threaded from the outer end for receiving a binding screw, 25, for the circuit wire connection, and reduced in diameter at the outer end to form a stem,

26, which extends through the casing wall and is flanged over a washer, 27, for securing the contact to the casing wall with insulating washers, 28, 28, interposed at opposite sides of said wall. The inner end of the contact is rounded over from inner to outer circumference at the inner end. The contact button, 20, has its head spheroidal, adapted to seat within the rounded annular inner end of the central contact, 22, and equally adapted to seat between the outer rounded edge of said contact, 22, and the outer rounded edge of either of the lateral contacts, 21 and 23, and to be snapped over the rounded edge of the central contact from one position to the other.

It will be understood that if a signal to be operated is contained in the circuit between the contact, 22 and the contact, 21, it will be energized by swinging the switch lever to snap the contact out of engagement with the contact, 22, and into the interval between the contacts, 22 and 21, and that any signals contained in the circuit between contacts, 22, and the contact, 23, will be energized by similarly snapping the button, 20, out of the contact, 22, and into the interval between 22 and 23.

The preferred or intended use of this switch device is for controlling a signal lamp which has two filaments for giving respectively a dim and a bright light, one of said filaments being in the circuit between the contacts, 22 and 21, and the other in the circuit between contacts, 22 and 23, as indicated in the wiring diagram, Figure 10, wherein the two-filament lamp is shown at 40. Any two different signals may, however, be similarly controlled, said signals being located in said two circuits respectively, said two controls being alternatively energized.

For mounting the casing on the support, such as the instrument board of the vehicle, and operating it and indicating to the operator the adjustment of the switch, whether at neutral position or for giving a dim or a bright light, a face plate, 30, is provided, having bolt apertures, adapted to be aligned respectively, through the board, A, with the apertures, 11^a and 12^a, of the casing, so that by means of bolts, 31, 31, and the face plate may be clamped upon opposite sides of the instrument board, A. It is designed that the shaft, 18, shall be primarily mounted in the face plate and secured therein by means of the operating handle lever, 32. And for this purpose the face plate has a boss centrally apertured for journaling the reduced end, 18^b, of the shaft, 18, the reduction of the shaft forming a stop shoulder at 18^c, a stop washer, 33, being interposed on the reduced end portion of the shaft between said shoulder and the inner face of the face plate which is desirably counterbored, as

seen at 35, around the bore through the boss for journaling the reduced end of the shaft. The shaft being inserted through said bore is driven into the hub, 32^a, of the operating handle, 32, the two parts being designed to be rendered rigidly secured together by this means, by the familiar expedient of knurling the end of the shaft, as shown at 18^b. For limiting the throw of the handle lever, 10 and thereby the angular movement of the switch, there is set into the boss, 30^a, of the face plate, a pin, 37, which projects from the boss into an arcuate slot, 32^d, in the lever, 32, as seen in Figure 8.

15 The shaft, 18, may be squared throughout its entire length from the inner end to the shoulder, 18^c, and thereby is adapted to telescope through the square aperture in the switch lever, 18, and through the bearings, 20 15 and 16, to any extent necessary to clamp the support between the casing members, B¹, B², and the face plate, 30; and the said shaft, 18, is designedly made long enough to accommodate a board, A, of the maximum 25 thickness likely to be found in the vehicle on which the device is to be mounted.

I claim:

1. In an electric switch device in combination with a mount, a spring switch lever 30 fulcrumed therein; a contact button carried by the spring arm of said lever insulated therefrom; three insulated contacts positioned on the mount in the arcuate path of the switch-carried contact button each 35 adapted for circuit wiring connections, said three contacts being shaped at their respectively approximate sides for snap engagement of the switch lever button between the middle and either extreme contact of the 40 three, the middle of said contacts and the switch button being relatively shaped for interlocking snap engagement with each other, at a position of the switch button out of contact with either of the extreme contacts, and manual means for turning the 45 switch lever to shift its contact button from position to position.

2. In the construction defined in claim 1 foregoing, the mount consisting of two 50 cupped and flanged casing members mated as to their cupping and flanging and secured together face to face for enclosing a chamber comprising the cup recesses of both members, journal bearings for the switch 55 lever mounted in the two casing members for alignment when said casing members are assembled, the switch lever being extended between said bearings for engagement with a rock shaft for operating the same, and 60 such rock shaft extended outside the casing provided exteriorly with an operating handle.

3. An electric switch for alternative closing of two circuits, comprising a casing, a 65 switch lever fulcrumed therein and carrying

a contact button; two contacts insulated on the casing in the arcuate path of the switch carrying contact button adapted for independent circuit-wire connections, means constituting circuit connections from said button for closing the circuits through the casing-mounted contacts, respectively; a shaft for the switch lever and journal bearings therefor within the casing, the switch lever being extended from the shaft between 70 said journal bearings, the shaft having an operating handle outside the casing and being non-circular in cross-section at and for a distance back from the end remote from the handle, the lever having a correspondingly non-circular aperture for rotative and sliding engagement with the shaft; whereby the shaft with its operating handle may be applied by inserting the shaft through the bearings and the switch lever aperture from the opposite side of a support on which the casing may be mounted, the varying thickness of such support being accommodated by varying length to which the shaft may be protruded through the said bearings and 80 switch lever and casing.

4. In an electric switch device for alternatively closing two circuits, in combination with a mount, a resilient switch lever fulcrumed therein; an insulated contact button carried by the switch lever, three contacts each adapted for circuit wiring connection insulated on the mount in the arcuate path of the switch-carried button, the 95 middle one of said contacts being shaped relatively to the button for interlocking engagement therewith by the reaction of the spring arm of the switch lever, the extreme contacts being positioned with respect to the middle for snap engagement between them respectively and the middle contact, and means for manual operation of the 100 switch lever.

5. In the construction defined in claim 4, foregoing, the mount comprising two casing members cupped to form a chamber of which part is in each member; the switch lever having a shaft which extends through said chamber; journal bearings in said chamber for said shaft positioned in alignment on the two casing members respectively, the switch lever being extended from the shaft between said journal bearings, and the three contacts being mounted on one of said casing members within said chamber.

6. In an electric switch device, in combination with a casing comprising two members united to form a chamber; a central carrying switch lever having journal bearings within the chamber mounted on and extending through the opposite walls thereof; insulating contacts mounted within the chamber having stems extended through the casing wall and adapted exteriorly for circuit wire connections; a shaft for the switch 125

lever slidably engageable therewith through the journal bearings and the casing walls; a face plate for mounting on the opposite side of the support from the casing, said face plate and casing having respectively registering apertures for bolts to clamp them together into an intervening support; whereby varying thickness of the support is

accommodated by varying the protrusion of the shaft through the casing and the switch 10 lever in its bearings.

In testimony whereof, I have hereunto set my hand at Chicago, Illinois, this 25th day of Sept., 1922.

WALTER VAN GUILDER.
